ATTORNEY

UNITED STATES PATENT OFFICE.

ALVIN E. BUCHENBERG, OF TOLEDO, OHIO, ASSIGNOR, BY MESNE ASSIGNMENTS, TO THE ELECTRIC AUTO-LITE COMPANY, OF TOLEDO, OHIO, A CORPORATION OF OHIO.

STARTING AND IGNITION SYSTEM.

Application filed May 21, 1919, Serial No. 298,670. Renewed July 26, 1923.

To all whom it may concern:

Be it known that I, ALVIN E. BUCHENBERG, a citizen of the United States, residing at Toledo, in the county of Lucas and State of Ohio, have invented certain new and useful Improvements in Starting and Ignition Systems, of which I declare the following to be a full, clear, and exact description.

This invention relates to an ignition system for an internal combustion engine, and particularly to a combined starting and ignition system for such an engine.

In systems involving an internal combustion engine as a prime mover driving an electric generator to charge a storage battery, a motor receiving its energy from the storage battery to start the engine, and an ignition system for the engine also receiving its energy from the battery, it is found that during the starting operation when the motor is drawing a relatively heavy current from the battery, the potential difference across the battery terminals is reduced to such an extent that the induction coil of the ignition system fails to receive sufficient current to produce a proper spark in the engine cylinder. It is an object of this invention to improve the efficiency of the induction coil in such a system, particularly during the starting of the engine, as by providing means whereby the reluctance of the magnetic circuit of the induction coil of such a system is reduced whenever the circuit of the starting motor is closed.

A further object is to so inter-connect the switch controlling the starting motor with means for decreasing the reluctance of the magnetic circuit of the induction coil, that the said means is moved to an effective position only when the switch is operated to close the motor circuit.

Further objects of this invention relate to economies of manufacture and details of construction, as will hereinafter appear from the detailed description to follow.

I accomplish the objects of my invention by the devices described in the following specification, but it is evident that the same may be varied widely without departing from the scope of the invention as pointed out in the appended claims.

A structure constituting one embodiment of my invention, which may be the pre-

ferred, is illustrated in the accompanying drawing forming a part thereof, in which:

Figure I is a diagrammatic view of a starting system and an ignition system receiving current from a common source, and illustrating one form of the invention.

Figure II is a plan on a larger scale of a detail of the apparatus shown in Figure I.

Figure III is a side view of a detail of a modification.

Figure IV is a plan of the modification shown in Figure III.

Figure V is a view similar to Figure IV, but showing a further modification.

In the drawing, similar reference numerals refer to similar parts throughout the several views.

Referring to Figure I, a storage battery 5, grounded at one terminal, is connected at its other terminal to a starting circuit 6 and to an ignition circuit 7. The starting circuit 6 includes a high torque series starting motor 8 having a series field winding 9, the opposite end of its circuit being grounded at 10. This motor is controlled by a push button switch 12 having a shank 13 carrying a spring 14 to keep the switch normally open.

The ignition circuit 7 is controlled by a switch 15 and includes a cam driven interrupter 16 in series with the primary of an induction coil 17, having primary and secondary windings. One end of the secondary winding is connected to a distributor 18 while the opposite end as well as one end of the primary is grounded all in the usual and well known manner. A yoke 20 of magnetic material is mounted on pivots 21 to swing in such a manner that the end portions of its two arms swing adjacent to the ends of the induction coils. This yoke 20 has an arm 22 to which is pivoted one end of a rod 23 pivoted at its other end to one arm 24 of a bell crank lever, whose other arm 25 is pivotally secured to the switch shank 13. A spring 26 connecting the upper arm of the yoke 20 with a stationary support, not shown, serves to hold the yoke normally in the retracted position shown in Figure II.

In the modification shown by Figures III and IV, a segmental shaped plate 30 of magnetic material takes the place of the yoke 20.

of Figure I. This plate is pivoted to a bracket 31 and is connected to the operating lever 23' by arm 22' while spring 26' serves to hold the plate 30 in a retracted position. 5 In Figure V the plate 30' has an oval shape, but otherwise is like that shown in Figures III and IV, having a spring 26' and an arm 22' as in the previously described modifications. 10 The operation of the device is as follows: When the starting switch is in its normal open position as shown in Figure I, the magnetic yoke 20 takes the position illustrated by Figure II in which position the reluctance 15 of the magnetic circuit of the induction coil is not materially decreased thereby. When the switch 12 is depressed to start the motor, the downward motion of the switch is communicated through the bell crank lever and 20 the rod 23 to rotate the yoke 20 to bring its two arms adjacent to the ends of the induction coil. In this position the reluctance of the magnetic circuit of the induction coil is reduced to such an extent and the efficiency 25 of the coil accordingly increased that even though the current taken from the storage battery is less than that necessary for proper ignition during the normal running conditions, a sufficiently strong ignition spark is 30 nevertheless obtained. As soon as the engine begins to operate under its own power, the starting switch is released and the magnetic yoke is automatically withdrawn from the coil. 35 While I have described my invention in more or less detail as being embodied in certain precise forms, I do not desire or intend to be limited thereto, as on the contrary, my invention contemplated broadly all proper 40 changes, as well as omission of immaterial elements, and the substitution of equivalents therefor, as circumstances may suggest or necessity render expedient.

Having thus described my invention, what

I claim as new and desire to secure by Letters Patent, is:

1. In a system of the class described, the combination of a starting motor, a switch therefor, an induction coil, a source of energy connected to supply both said motor and said coil, and means operatively connected with said switch for varying the reluctance of the magnetic circuit of said coil. 50

2. In a system of the class described, the combination of a source of energy, an induction coil in circuit therewith, a translating device connected with said source in parallel with said coil, a switch in the circuit of said device, and magnetic means for partially closing the magnetic circuit of said coil when the said switch is closed. 60

3. In a system of the class described, the combination of a battery, an induction coil in circuit therewith, a starting motor connected with said battery in parallel with said coil, a switch for controlling the circuit of said motor, magnetic means adapted to be moved into a position to increase the permeability of the coil, and a connection between said switch and said magnetic means whereby when the switch is operated, the efficiency of the coil is increased. 65

4. In a system of the class described, the combination of a source of energy, a starting motor and a controlling switch in circuit therewith, an ignition system comprising an interrupter and an induction coil also in circuit with said source, said induction coil having a core and a magnetic member movably mounted to partially bridge the ends of said core and an operative connection between said switch and said magnetic member whereby when said switch is closed the magnetic member is moved to a position to partially bridge the ends of said core and the effectiveness of said coil increased. 70 75 80 85

In testimony whereof, I affix my signature.
ALVIN E. BUCHENBERG.
